ELECTRICAL WALL PLATE

Walter V. Legan, Stamford, Conn.

Application January 21, 1958, Serial No. 49,337

Term of patent 3½ years

(Cl. D26—13)

Fig. 2.

Fig. 1 is a front view of an electrical wall plate showing my new design;

Fig. 2 is an edge view thereof with a portion of the plate shown in section.

I claim:

The ornamental design for an electrical wall plate, substantially as shown.
